E. SCHMITZ.
PULVERIZING FUEL.

No. 12,286.

Patented Jan. 23, 1855.

UNITED STATES PATENT OFFICE.

ELOY SCHMITZ, OF NEW YORK, N. Y.

APPARATUS FOR SUPPLYING FURNACES WITH PULVERIZED MATERIAL.

Specification of Letters Patent No. 12,286, dated January 23, 1855.

To all whom it may concern:

Be it known that I, ELOY SCHMITZ, of the city, county, and State of New York, have invented a new and improved apparatus for supplying forge and other blast furnaces or fires with pulverized coal, oxids, or other substances to aid in the combustion or the reduction of ores, &c., of which the following is a full, clear, and exact description, reference being had to the accompanying drawings, making part of this specification, in which—

Figure 1, is a side elevation; and Fig. 2, a longitudinal vertical section.

15 The same letters indicate like parts in both the figures.

The object of my invention is to introduce pulverized coal, or oxids or other substances into forge or other fires, excited by a blast, 20 whether such pulverized substances are to be introduced for the purpose of combustion or for the chemical change of the matter or matters under treatment.

By my said apparatus the pulverized substance is placed in a hopper from which it falls into the threads of a horizontal screw conductor which conducts it to a vertical tube called the charging tube which is provided with a valve at bottom, which is alternately opened to discharge into a horizontal tube called the discharge tube and placed within the blast pipe leading to the furnace so that the blast shall carry the pulverized substance to the furnace, the said discharge 30 tube being provided with valves at the ends which are closed while the valve of the charging tube is open to permit the descent of the charge, and which, so soon as the valve of the charging tube is closed, are 35 opened that the blast may carry the substance to the furnace, the valve of the charging tube preventing the blast from entering the charging part of the apparatus.

Above the discharging tube there is a branch 40 pipe opening into the atmosphere and governed by a valve which is opened when the valve of the charging tube is opened that any pressure of air in the apparatus due to the blast before it is shut off, and which, if 45 not permitted to escape, would impede the descent of the pulverized substance from the charging tube. The descent of the substance from the charging tube is aided by the working of a punch rod within the charger.

50 In the accompanying drawings A', B', represent a hopper which is to contain the

pulverized substance to be introduced, the delivery aperture V, of which hopper is situated directly over one end of a horizontal screw conductor Q, which conducts the said 60 pulverized substance and discharges it into a vertical tube N, in which it is held by a valve J, at bottom to be presently described. The shaft D, of the endless screw has a spur wheel C, which receives a slow motion from 65 a pinion A, on the shaft of a driving pulley B, which receives motion from some first mover. The inner end of the shaft D, of the screw conductor is provided with a small crank R, which carries a punch rod S, that 70 is thus worked up and down in the tube N, to prevent the pulverizing substance from clogging therein.

The tube N, is surrounded by an outer cylindrical casing O, which at top spreads 75 out to form the casing surrounding the screw conductor above described. The top of this casing is covered with a plate e, f, which supports the hopper A', B', by means of vertical rods g, g. The said plate has an 80 aperture directly above the tube N, governed by a cap plate W, turning on a screw pin h, to give access to the tube N, for inspection. And the case O, has a hole in the line of the shaft D, covered by a plate X, to give 85 access when required, to the screw conductor. The tube N, is made separate from and properly fitted to the casing O, and kept in its proper position by set screws b, b.

The lower end of the cylindrical casing O, 90 has a flanch secured by bolts d, d, to the upper surface of a horizontal blast pipe Z, through which the blast, from some suitable blower passes, one end of the said blast pipe being suitably connected with a blower and 95 the other with the furnace or fire so that the blast passes through the said pipe in the direction of the arrow.

In the center of the blast pipe Z, there is a small tube P', which is a horizontal branch 100 of a continuation P, of the vertical casing O, properly fitted to its lower end and secured by screw bolts c, c.

On a line with the lower end of the tube N, there is a short horizontal branch T, of 105 the cylindrical part of the case O. The lower end of the tube N, the outer end of the branch T, and the two ends of the horizontal tube P', are beveled off to an angle of about 45 degrees, and to each of these 110 beveled ends is fitted a hinged or flap valve indicated on the drawings by J, I, M, and

L. The two valves J and I, are connected together by a connecting rod t, and the other two M and L, by a connecting rod U, the rods being so connected that J and I, will 5 open and shut together, and so with M and L. The valve I, is provided with an arm and wrist pin which fits in a cam groove in the face of a wheel H, by which it is opened and shut; and the valve L, is governed 10 in like manner by a cam wheel K, and both of these cam wheels are mounted on a vertical shaft E, which receives motion by bevel wheels F G, from the shaft D, of the screw conductor. The cam wheel K, is 15 within the blast pipe Z, and to prevent the escape of wind the shaft E, is surrounded by a stuffing box a. The cam grooves in the two wheels H, and K, are such that when the valves J and I, are open the valves 20 M and L, are closed, and vice versa.

The apparatus being set in motion and the hopper charged with the pulverized substance, say coal, it will fall from the hopper onto the screw conductor by which it will 25 be conducted and discharged into the vertical tube N, in which it is kept free and loose by the punch rod S. The valves M, and L, are then closed which prevents the blast from entering the horizontal tube P', 30 and the valve J, being opened the charge in the tube N, falls into the horizontal tube P', the valve I, being at the same time opened to form a communication with the atmosphere so that the falling of the substance 35 may not be prevented by any excess of pressure due to the blast before the valves M, and L, were closed. The valves J and I, are then closed, to shut off all communication with the upper part of the apparatus 40 and the atmosphere, and immediately after the valves M and L, are opened so that the blast of air may pass through the central tube P', to carry the pulverized coal or other substance out and into the fire. In

this way successive charges of the pulverized substance is deposited in the tube P', 45 and then exposed to the force of the blast to be carried to the furnace.

Having thus described the construction and mode of operation of my invention I 50 do not wish to be understood as limiting myself to the special construction and arrangement of the parts so long as the same ends are attained by merely formal changes.

What I claim as my invention and desire 55 to secure by Letters Patent is—

1. Arranging within the blast pipe of a furnace or other fire place another and smaller pipe or tube governed by valves to admit and cut off the blast, substantially as 60 described, when this is combined with the charging tube also governed by a valve, substantially as specified, so that when the blast is forcing the pulverized substance from the tube within the blast pipe, the blast 65 shall be cut off from the charging tube, and when the charging tube is open for the liberation of the charge the blast shall be cut off by the valves below, as set forth.

2. And I also claim in combination with 70 the above charging and discharging tubes governed by valves, the employment of a branch tube governed by a valve opening to the atmosphere, to prevent the pulverized substance from being held in the charging 75 tube by any excess of pressure which may be due to the entrance of the blast during the time the valves of the discharging tube are opened, as set forth.

3. And I also claim in combination with 80 the discharging and charging tubes the employment of the conductor, and the punch rod, substantially as described and for the purpose set forth.

E. SCHMITZ.
